6684X

I. FOBES.
STAVE JOINTER.

Patented Aug. 3, 1831.

6684X

James Hobbs, Bridgewater, Massachusetts

Solders' Patent.

The Schedule, referred to in these Letters Patent, & making part of the same, containing a description in the words of the said James Hobbs himself of his improvement called the Slave Sinker.

To all to whom these precedents shall come.

Be it known that I, James Hobbs, of Bridgewater, in the County of Plymouth and State of Massachusetts, have invented, caused to be made, and applied to use, a new and useful improvement in the art of Loop = ring or of making Barrels or Bushes; which consists in sinking the staves by a machine which shall have Slave Sinker, and that the following is a full and exact description of the construction and operation of the said Machine as invented by me. This Sinker is constructed in the form of a wheel or section of a hollow sphere to turn on an axis which passes through the center thereof. The jointed face or cutting side thereof should be turned out in a concave form like or similar to the inner surface of a common watch crystal, or (to form the staves a little straighter near the ends so that the stain shall come on the shime loop of the bush) the face of the Sinker should be somewhat flatter or less concave toward the periphery approaching the form of a trumpet mouth. Said wheel or Sinker is perforated near its periphery and at proper distances to receive four or more bushes iron or cutlers which are held in their place by wedges or screws, and the edges thereof are ground and adjusted to correspond to the concavity of the face of the Sinker so that when the jointed iron is caused to revolve quickly on its axis by the application of power thereto (by means of a crank, pulley and bell or gear) and the edge of a stave is properly held against the face thereof in the direction of a tangent line to the circle of the jointed the cutting edges, or projecting therefrom will each in succession cut shavings from the stave and thus immediately reduce its whole length to the required

time

level and curve at the same operation; after which the staves
is to be shifted so as to bring the other edge thereof in like manner
in contact with the counterface where a like operation complete
the bending of the staves. The dimensions and concave form of
the jointer may vary according to the sizes and proportions of the
casks for which the staves to be jointed therewith are intended
A convenient one for bending barrel staves should be about seven
feet in diameter with a rim a foot deep and three or four inches thick
and bolted to the ends of two pieces of scantling locked together in the
middle in the form of a crop and this constituting the four arms
of the wheel or jointer. An iron shaft is firmly fixed in the center
of the wheel and constitutes the axis. The rim is perforated to receive
four or more counter irons or cutters of such width or so arranged
that nine inches of the depth of the rim or jointer face may at least
twice in the course of a revolution present a cutting edge to a stave
which may be held against any portion of the said depth. The depth
of concavity should be about one inch and a half in the depth of rim
here spoken of. Two upright posts properly secured at top and bottom
to the building in which the jointer operates, or to any other fixtures,
form supports in which the jointer axis turns; and in the front
post at half the length of the stave below the axis is framed a timber
which extending close by the face of the jointer in nearly a horizontal
direction to the length of the semi-diameter of the jointer and forming
rests on which the end of the staves stands during the process of join-
ing, in this rest and close to the jointer face are inserted in a per-
pendicular direction two or more guide pieces between which the staves
are placed and which serve to aid the workman in holding it in the right
position while bending. The reason why I have recommended so great a
depth of jointer face and extent of cutting edge is that there are few
generally different widths of staves in the same cask and in order
to give each its proper form the narrow staves should be held near
the periphery during the process of bending, and so the wider on
more toward the axis. The proper position however to form

the

the stave to the curve and bent desired is properly attained by the workman and as each will proportion his cuts to with his own fancy, a further description seems not to be useful. I would observe however that the concave surface of the jointer may be made sufficiently deep or extensive and have a corresponding number of cutters inserted therein to joint staves for any sized basket with the same jointer if it be desired; and may revolve either in a vertical, horizontal, or oblique position.

What I claim as my own original invention is the principle by which the requisite curve is given to the whole length of the stave at one operation by cutters adjusted to a concave or convex wheel and secured thereto while the said wheel receives a rotary motion during the process of jointing the stave - which principle I apply in the concave jointer constructed and used agreeably to the foregoing specification.

In testimony of all which I hereunto set my hand and seal this day of July in the year of our Lord one thousand eight hundred and thirty one, at Bridgewater aforesaid.
